UNITED STATES PATENT OFFICE.

H. HENRY RIEPEN, OF BUSHNELL, ILLINOIS, ASSIGNOR OF ONE-HALF TO JOSEPH KATZENSTEIN, LOUIS KAISER, AND GUSTAVUS A. KAISER, ALL OF SAME PLACE.

AUTOMATIC GRAIN-SCALE.

SPECIFICATION forming part of Letters Patent No. 363,766, dated May 24, 1887.

Application filed July 12, 1886. Serial No. 207,795. (Model.)

To all whom it may concern:

Be it known that I, H. HENRY RIEPEN, a citizen of the United States of America, residing at Bushnell, in the county of McDonough 5 and State of Illinois, have invented certain new and useful Improvements in an Automatic Grain-Measurer, of which the following is a specification, reference being had therein to the accompanying drawings.

10 My invention is an automatic grain-meter, and embraces, in brief, the following novel features: The box measure or casing surrounded by a hopper-opening and having a rigid median partition rising vertically and 15 from its open base and above its swelling and tapering spout; also, a vibrating trap-door having its lower edge contiguously pivoted along the top edge of said rigid partition, and its top edge swinging from side to side and 20 resting on either side of said casing; also, a triple-planed trap-floor pivoted at the angle meeting of its top planes along the lower edge of said rigid partition and oscillated by the regulated weight of cumulative grain; also, 25 said oscillating floor furnished with a forked and vibrated bar, and with a pair of spring-latches secured one to each end of said trap-floor; also, a pair of graduated lever-beams, suitably hung one on each side of said open-base of the casing, and furnished each with a set-screwed scale-weight; and, finally, said box apparatus furnished with an automatic register, the train of which is suitably secured upon either side of said box and contiguously 30 above the latched end of said oscillating trap-floor, all of which and their purposes are hereinafter more fully described, and illustrated by the accompanying drawings, in which like letters designate identical parts of 35 said invention in the different figures, respectively.

Figure 1 is a front view of the said device with the front cover of the casing broken out, showing the vibrated part or trap-door of 40 said rigid partition in connection with its reciprocally-moving and trap-floor connection-bar and the said oscillating trap-floor beneath, also the pair of lever and catching scale-beams and the register-train attached to one side 45 of said casing. Fig. 2 is the side view of the

same device, showing a front view of said register and an end view of one of said pair of weighing-beams.

The letter A represents said measure box or casing, which is made of suitable materials 55 and of the general shape shown. The rectangular body of said box has the hopper-shaped rim B, introduced into its top, for the purpose of properly conducting the inpouring grain from a leading-spout or elevator into said 60 measuring-box, the open base of which swells outwardly on each side and then tapers inwardly by equal angles, as shown, into an outwardly-conducting grain-spout, C, when 65 said grain has been measured or weighed and released from said casing, as hereinafter described. The casing is also divided into two 70 equally-sized and alternately-measuring compartments, a and a', by the said rigid partition b, which rises parallel with the sides of the box-body from the horizontal line of its open base, as shown, and is surmounted by said swinging trap-door c, pivoted by the axle-rod r, so that 75 its lower edge bears upon the top edge of said rigid partition, as shown, while its upper edge is caused to swing alternately from one side of the casing to the other, or allowed to rest against either side, as shown. This alternated motion and rest—for the purpose of alternately 80 opening and simultaneously closing the respective upper passages into said compartments a and a', in order to alternately fill and empty the same, one with grain for measurement and the other of grain after measurement—is produced as follows: The trap-floor 85 D of said casing is made of a suitable framework of wood and of the transversely-triangular shape shown. Said floor is medially hung at the meeting angle of said equally-inclined top planes or trap-floors by the hinging-lugs e upon the pivot-rod r', extending through the groove g, made into the lower edge of said rigid partition, as shown. Again, said oscillating platform D is provided with the connecting-bar E, the bifurcated end of which is 95 suitably fastened to the front of said platform, so that when the base of the same is horizontal the said connecting-bar will be in a vertical position. Said bar E is also provided with the slide slot m, cut through the end opposite 100

to said bifurcation, and which incloses and engages the pin *p*, projecting, as shown, from the front edge of said swinging trap-door through the arching slot *n*, so that when motion is reciprocally conveyed by said alternate oscillations of the platform *D* through connecting-bar *E* to the pin *p* said pin freely slides along the arched slot *n*, transmitting an alternately swinging motion to said trap-door *e*, thereby alternately opening and closing the respective upper passages into said compartments *a* and *a'*, while the said basal passages of the same are being alternately and oppositely opened and closed by the oscillation of the platform *D*; also, thereby in turn shutting off the grain from one compartment, while allowing the measured grain to pass simultaneously from the other compartment into and through said conducting spout *C*, as shown.

In order to secure each trap-floor of said platform in horizontal position, and thereby to close up the lower opening of its respective compartment *a* or *a'*, and to fill the same with grain for measurement, a pair of spring-latches, *l*, are suitably secured one on each swinging end of said platform, as shown, and as each latch is thus swung upward by the rising end of said platform it engages the projecting and beveled end of one of the said pair of lever-beams *F*, and, springing over the same, is latched upon the top edge thereof, as shown, where it remains caught until the weight of the grain in the filled and measuring compartment above causes its trap-floor to overbalance the said weighted and weighing lever-beam, thereby unlatching said oscillating floor-platform and allowing the weighed or measured grain to drop through the conducting-spout, as shown. Simultaneously with the depression of the trap-floor of said emptying compartment the oscillation of said platform causes the opposite compartment trap-floor to rise and be latched upon the other of said pair of lever-beams, which oscillation also vibrates the said connecting-bar *E*, which causes the trap-door *e*, resting on the opposite side of the casing to that over the filled and now emptying compartment, to swing to the other side of the casing, thereby to close the upper passage to said emptying compartment, and also to form a slide to conduct the grain falling through said hopper-opening above into the now trap-closed and filling compartment.

The above described process of weighing or measurement may be continued as long as desired and the grain is allowed to run, the said lever-beams being each so pivoted that its shorter and floor-catching arm is regulatively overweighted by a sliding and set-screwed cylinder, of suitable metal, hung upon its longer

and graduated arm, these scale-weights being each made of sufficient gravity and so poised upon said scale-beams as to exactly balance the estimated weight, and therefore the number of bushels, of the grain in either of said filled compartments, together with the friction of said latched and oscillating apparatus.

In relation to and in connection with said weighing and measuring apparatus a registering device is added, as follows: A train of two wheels suitably secured upon either side connectively above said latching scale-beams, as shown, the one wheel, *w*, being a ratchet-pinion worked by a sliding angle-armed pawl, *v*, pressed upwardly by the alternately-rising trap-floor of the oscillating platform *D*, and the other wheel, *w'*, a regulatively-cogged pinion engaged by the bars of the ratchet and trundle wheel *w*, and having its cogs, or the intervals between the same, regularly and successively numbered, as shown, to thereby indicate the number of oscillations of said trap-floor platform, and consequently the quantity of grain measured. Therefore,

What I claim as new, and desire to secure by Letters Patent, is—

1. In the box-casing of the grain-meter having the hopper-opening, the swelling and tapering spout, the rigidly-secured median partition, and the arching slot herein described, the combination of the oscillating floor-platform having the pivot-rod and end-projecting spring-latches with the forked and slotted connecting-bar, and with the swinging trap-door surmounting said rigid partition and having the engaged swing-pin, substantially as and for the purposes herein specified.

2. The combination of the oscillating floor-platform having the end-projecting spring-latches, with the trap-floor and grain supporting and balancing lever-beams, each having sliding and set-screwed weights regulatively adjustable upon its graduated longer arm, substantially as and for the purposes herein specified.

3. The combination of the oscillating pair of inclined trap-floors of the pivoted platform having the projecting spring-latches with the angle-armed and vertically-sliding pawl of the graduated train-wheels of the register, secured upon said box-casing just above the graduated and grain-balancing lever-beams, substantially as and for the purposes herein specified.

In testimony whereof I affix my signature in presence of two witnesses.

H. HENRY RIEPEN.
